J. ROCKE

WASHING MACHINE WRINGER MECHANISM

Filed Dec. 17, 1923

Inventor.
By John Rocke
Leffler & Leffler
Attorneys.

UNITED STATES PATENT OFFICE.

JOHN ROCKE, OF BLOOMINGTON, ILLINOIS.

WASHING-MACHINE WRINGER MECHANISM.

Application filed December 17, 1923. Serial No. 681,055.

My invention relates to a washing machine wringer mechanism and more particularly to a wringer of the safety type.

The object of my invention is in the provision of a washing machine wringer having a simple and quickly releasable safety mechanism mounted in connection therewith.

Another object of my invention is in the combination of a conventional spring mechanism for tensioning the rolls on a washing machine wringer and a demountable mechanism in connection therewith adapted to be positioned as desired by the operator.

Still another object of my invention is in the provision of a wringer having a safety mechanism in connection therewith that includes a single quickly releasable bolt member.

Another object of my invention is in the provision of a wringer mechanism having a safety mechanism connected therewith in such manner as to be positioned for quick release either by a left or right handed operator.

Other objects of my invention will appear in the following specification taken in connection with the annexed drawings, in which Figure 1 is a front elevation of my wringer, portions of which are shown in section for a more detailed showing.

Figure 2 is an enlarged detail partially in section of my specific safety release mechanism.

Figure 3 is a plan of a portion of the wringer with the safety release bolt removed.

Referring to the drawings:

I have shown in Figure 1 a wringer mechanism of usual design except for the safety mechanism attached thereto.

My wringer is made up of the cast end plates 10 and 11, the end plate 11 having the projecting portion 12 which provides one of the bearings for a drain pan (not shown) adapted to be disposed thereunder.

The end plates 10 and 11 are fashioned to receive the bearing blocks for the roll members to be described and as a matter of fact these end plates form guide ways for said bearing blocks. Means for connecting the end plates together and at the same time providing a guard adjacent the wringer rolls, are found in the transversely disposed plates 12 and 13. These plates make up the lower

part of the wringer, while the upper portion includes a cover 14 rounded at the top and fastened to each of the end plates by suitable screw members. In the guide ways fashioned in the end plates 10 and 11 are placed the bearing blocks 15 and 16 for the lower roll and 17 and 18 for the upper roll respectively.

The lower wringer roll 19 is of conventional design and is power driven from the usual drive mechanism, not shown. The upper roll 20 is driven from the lower roll thru the conventional gears 21 and 22. A guard plate 23 perforated as at 24 surrounds the gears and is bolted to the end plate 10 in such manner as to permit the projecting portion 25, to co-operate with the projecting end portion 25^a on the end plate 11, to support the usual drain pan, not shown. Means for applying tension to the upper wringer roll is provided in a transversely disposed flat spring 26 and in connection with this spring I have provided my special release mechanism for making up the safety device for the wringer.

Pinned intermediate the ends of the transverse spring 26 is a receiving lug 27 against which the spring tensioning mechanism, now to be described, bears.

My spring tensioning and releasing mechanism consists in a demountable bolt which includes a tubular key member 28 having its interior threaded as at 28^a and a screw member 29. The key includes a main hub portion 30 having a handle 31 projecting therefrom in an exposed position. Upon the exterior surface of the key are formed pairs of wards respectively indicated as 32 and 33 projecting laterally and spaced some distance apart, each pair being in the same plane and disposed on a line thru the axis of the key. However, said pairs are disposed in different longitudinal planes for reasons hereinafter specified. The tension screw is entered thru the hub 30 and is adapted to project against the receiving lug 27 upon the flat spring 26. The tension screw has a manually operable tension wheel 35, which is adapted to rotate same. Inserted in an opening in the upper portion of the wringer frame is a plate or key seat 36, said plate being positively fastened to the upper portion 14 of the frame by means

of the screw members 37 and 38. The plate or key seat 36 has a central opening 39 therein, as shown in Figure 3 of the drawings. This opening is relatively proportioned with respect to the key so that the latter is capable of entry thereinto and is provided with wards 39^a spaced at regular intervals about aperture 39 to facilitate the entry of the ward members of the key. This being accomplished, by retracting the screw member into a position so that the key may be entered thru the opening 39 in plate 36 a sufficient distance before contact with the lug 27 or bar spring 26 that the key may be turned so that its upper set of wards engage the intervening portions of said plate between the wards in the plate, then by rotating screw 39, tension may be applied to spring 26. The relative arrangement between ward members respectively of the key and plate is such that the former may not be entered thru the plate except that it shall be turned into a certain definite position and in the instance where shown in a position angular with respect to the length of the wringer frame so that when the key is entered it may be turned into substantially a right angle position with the length of said frame when the wards thereon will be opposed to the intervening portions between the wards in the plate thereby when the screw is projected locking the key in connection with the plate and whereby the handle portion 31 of the key will project in substantially parallel line with the length of the frame. The lower wards are positioned in a different longitudinal plane from the upper wards so that when handle 31 is turned into a position whereby the upper wards are permitted to pass thru the wards in the plate, the tension of the spring acts to violently project the bolt, so that the lower wards will engage the intervening portions of the plate to prevent the bolt from being wholly dislodged.

To release the above safety mechanism it is merely necessary to strike the release handle sharply in either direction, or rather to move it to such an extent as to permit release of the bolt, which takes place when the wards 32 are moved in such manner that their upward movement thru the plate 36 is permitted. In other words, the striking of the release handle permits partial expulsion of the bolt from the wringer, or rather upper casing thereof. However, the entire expulsion of the bolt is prohibited, due to the fact that the lower set of wards upon the upward movement of the bolt abut the underside of the plate 36. With the wringer in its released position, to entirely withdraw the bolt from the wringer, it is only necessary to move the release handle to such a position as to permit the further withdrawal of the lower set of wards thru the plate 36.

I have provided a demountable bolt and tensioning mechanism which makes up the safety portion of my wringer for the purpose of providing a mechanism that may be set at either side of the wringer as desired. The above described mechanism, due to its demountable feature, may be inserted as shown in Figure 1, into the wringer in such position that the release handle thereof may extend at either side of the wringer as desired. This has been provided in case the operator, we will say, is left-handed, or for any reason where it is desirable that the release handle be placed in an opposed position.

I have described the manner of positioning the bolt or rather safety mechanism relative to the transverse spring but it might be said here that after release of the bolt and hence the tensioning screw 34 it is necessary to withdraw said tensioning screw to some extent to permit the entire insertion of the bolt thru the plate 36. When the bolt has been placed in its normal position and moved to a position to prevent its upper movement thru the plate 36, the tensioning screw is again inserted into the receiving lug 27 until the desired tensioning of the wringer rolls has been obtained.

As said before, if it is desired that the release handle be placed in an opposite position upon the wringer, it is merely necessary to release the tensioning screw, move the release handle to the desired position and again apply tension to the spring.

There is an added advantage in having my bolt and tensioning screw demountable, in that assembly is made much simpler. Again, there are advantages in shipment, packing, storage, etc.

What I claim is:—

1. In a wringer, in combination a wringer frame including a top frame member, an adjustable roll supported in the frame, a removable spring tension member for imparting pressure to said roll, an elongated key seat supported in the top frame member provided with wards therein, a removable key for entry within said key seat and provided with longitudinally spaced pairs of lugs, each pair arranged in different transverse planes, and adapted to be entered through the key seat and locked by circumferential manipulation of the key and provided with an axially disposed threaded bore, and also provided with a laterally projecting striking arm; a pressure screw threaded in and extending through the key adapted for projection into contact with the spring tension member to apply pressure thereto.

2. In a wringer, the combination of a frame, a roll adjustably mounted in the frame, a leaf spring for imparting pressure to the roll, a key seat fixed to said frame

and provided with wards, an elongated key having a set of lugs cooperating with said wards to permit the key to be inserted longitudinally into the key seat and locked and released by rotation of the key, a striking arm connected with the key, said key having a second set of lugs spaced longitudinally

from said first mentioned set and in staggered relation thereto, to limit the longitudinal movement of the key when it is released, and means engaging said key and said spring for compressing said spring.

In testimony whereof I affix my signature.

JOHN ROCKE.
